UNITED STATES PATENT OFFICE.

ROSCOE R. RANSOM, OF DALLAS, TEXAS.

FOOT REST.

Application filed May 27, 1921. Serial No. 473,093.

To all whom it may concern:

Be it known that I, Roscoe R. Ransom, a citizen of the United States, residing at Dallas, in the county of Dallas and State 5 of Texas, have invented certain new and useful Improvements in Foot Rests, of which the following is a specification.

This invention relates to new and useful improvements in foot rests.

10 The object of the invention is to provide a foot rest to be used on shoe shining stands and arranged to clamp or fasten the shoe of the customers on the rest so that the boot black in shining the shoe cannot displace 15 the same from the rest. A particular feature of the invention is to arrange the device in such a manner that the customer by pressing downwardly and forwardly on the rest causes the clamping mechanism to grip the sole of the shoe; and by 20 merely lifting his foot the sole is automatically released.

A construction designed to carry out the invention will be hereinafter described together with other features of the invention.

The invention will be more readily understood from a reading of the following specification and by reference to the accompanying drawings, in which an example of the 30 invention is shown and wherein:

Fig. 1 is a side elevation of a device constructed in accordance with my invention, the releasing position being illustrated in full lines and the clamping position in dotted lines,

Fig. 2 is a front elevation of the device,

Fig. 3 is a partial plan view on an enlarged scale.

Fig. 4 is a side elevation of the parts 40 shown in Fig. 3,

Fig. 5 is a cross sectional view on the line 5—5 of Fig. 3, and

Fig. 6 is a cross sectional view on the line 6—6 of Fig. 3.

45 In the drawing the numeral 10 designates a base which may be of any suitable construction. A pair of transversely spaced brackets 11 are mounted on the base and have pivoted therebetween the enlarged foot

50 12, of a standard 13. A pair of spaced brackets 14 are also mounted on the base and have pivoted therebetween the enlarged foot

15 15 of an upright 16. The upright 16 is bifurcated so as to receive between its upper end a brace 17, to which the upright is pivoted. The brace is diagonally disposed and

has its lower end pivoted in the standard 13. It will be seen that the said parts 13, 16 and 17 constitute a swinging support.

A foot plate 18 is provided with a bracket 60 19 which is fastened to the rear portion of the plate 18, and pivotally receives the upper end of the brace 17. The plate 18 has a depending flange 20 at its rear end which acts as a stop to receive the front edge of 65 the heel of the operator.

A clevis 21 is mounted on the upper end of the standard. The forward ends of clamping links 22 are overlapped and pivoted in the clevis. These links have their 70 rear portions curved laterally in opposite directions so as to project on each side of the plate 18. Each link has a curved slot 23 receiving a pin 24 extending downwardly from the plate 18. A keeper 25 under the plate 18 supports the links and holds them in position on the pins. Each link has an angular inwardly bent clip 26 on its outer end disposed so as to engage the instep of the sole of a shoe which is placed on the 80 plate 18.

It will be seen that by pressing downwardly on the plate 18, the standard 13 and upright 16 will be swung forwardly, but the upper end of the standard 13 being at a 85 greater elevation than the upper end of the upright, will swing to a greater degree. When the swinging movement takes place the upper end of the brace 17 will be swung downwardly and rearwardly with relation 90 to the standard 13. The result of this will be that the brace will tend to pull the plate 18 rearwardly while the clevis 21 will pull the links 22 forwardly. Owing to the engagement of the pins 24 in the curved slots, 95 it is obvious that the links will be drawn inwardly as they are pulled forwardly, whereby the clips will clamp over the edges of the sole of the shoe and thus hold the shoe on the plate 18. A coiled spring 27 extending 100 from the upright to the brace is placed under tension when the parts are swung and, therefore, when pressure is relieved on the plate 18, said spring will swing the parts back to their normal position; whereby the links will 105 be spread and the sole of the shoe released. The device is automatic in its operation as well as positive and simple.

Various changes in the size and construction of the parts as well as modifications, 110 may be made without departing from the spirit of the invention.

What I claim, is:

1. In a foot rest, a swinging support, a foot plate, and a pair of movable clamping members disposed on opposite sides of said plate for engaging and holding the shoe on the operator's foot when said support is swung.
2. In a foot rest, a swinging standard, a swinging upright, a brace pivoted to the standard and also pivoted to the upright, a foot plate pivoted to the brace, and clamping members connected with the standard and straddling the foot plate, a coiled spring connecting the brace with the upright.
3. In a foot rest, a pivoted standard, a pivoted upright, terminating below the upper end of the standard, a brace to which the upright is pivoted, said brace having its lower end pivoted to the standard, a foot

plate having its rear portion pivoted to the upper end of the brace, clamping links pivoted to the upper end of the standard and having curved slots, and pins carried by the foot plate and engaging in the slots of the clamping members.

4. In a foot rest, an upright support adapted to be swung forwardly by pressure exerted by the foot, a foot plate, a pair of clamping members disposed on opposite sides of the plate and connected with the support, means secured to the underside of the foot plate for actuating the clamping members when said support is swung, and automatic means for returning said support and clamping members to normal position when said pressure is released.

In testimony whereof I affix my signature.
ROSCOE R. RANSOM.
